UNITED STATES PATENT OFFICE.

CANUTE OLSON, OF CHICAGO, ILLINOIS, ASSIGNOR OF ONE-HALF TO THE
TOBEY FURNITURE COMPANY, OF SAME PLACE.

SMOKE-CONSUMER.

SPECIFICATION forming part of Letters Patent No. 254,037, dated February 21, 1882.

Application filed October 28, 1881. (No model.)

To all whom it may concern:

Be it known that I, CANUTE OLSON, a citizen of the United States, residing at Chicago, in the county of Cook, in the State of Illinois, have invented certain new and useful Improvements in Smoke-Consumers, which are fully set forth in the following specification, reference being had to the accompanying drawings, in which—

10 Figure 1 is a front elevation of a boiler and furnace provided with my apparatus. Fig. 2 is a partial section on the line $x-x$ in Fig. 1, the structure being broken away back of the fire-box, and the boiler not being in section, but 15 the lower front part of it being entirely broken away. Fig. 3 is a section on the line $y-y$ in Fig. 2, only the lower left-hand quarter of the structure being included. Fig. 4 is a plan section on the line $z-z$ in Fig. 3. Fig. 5 is a detailed 20 section on the line $v-v$ in Fig. 3, so as to give a plan view of the upper end of the steam-coil. Fig. 6 is a perspective view of the shoe which 25 supports the steam-coil, and of that part of the grate on which it rests. Fig. 7 is a front elevation of the cap or nozzle through which the steam is discharged.

The same letters denote the same parts in all the figures.

My invention relates to means for consuming 30 smoke and other combustible matter which passes off unconsumed from ordinary furnaces; and it consists in apparatus of special construction and arrangement for accomplishing this result by throwing an unbroken horizontal 35 sheet of superheated steam over the fire just above the coals. The construction, arrangement, and operation of the apparatus employed by me for this purpose will first be fully described, and the special improvements, which 40 I believe to be new and desire to secure by Letters Patent, will then be pointed out more definitely in the claims.

In the drawings, A denotes a steam-boiler, and a its steam-dome. B denotes the furnace; 45 b , the fire-doors; b' , the grate-bars, and b^2 the bridge. All these may be of ordinary construction.

C is a steam-supply pipe passing from the dome down in front of the boiler and into the 50 furnace, preferably at one side. The lower horizontal portion, c , which enters the furnace, is

preferably somewhat larger than the rest. If the upper part be, for example, three-eighths of an inch in diameter, I find it advisable to make the diameter of the part c half an inch. 55 A valve, c' , at any convenient point in the length of the pipe, regulates the supply of steam. Within the furnace the pipe c is directed to a point over the nearest corner of the grate and there enters the lower part of a steam-coil, D, which is supported on a shoe, D' , resting on the grate-bars at one side of the grate. The shoe is secured in position by a bolt, d' , and a nut on the under side of the grate, or by other convenient means. The coil is arranged 60 on the inner side of the fire-box, directly over the grate, the number of turns being greater or less, according to the degree to which it is desired to heat the steam. In the construction shown in the drawings, which I find satisfactory in practice, the coil passes twice straight upward and once straight downward. At the end of the second upward pass the pipe is carried horizontally across to the boiler, thence straight downward a short distance, and thence 65 horizontally back to the wall at the corner of the fire-box, and down again to a point somewhat above the coals which rest on the grate and about on a level with the point where the pipe C enters the furnace. Here it turns again 70 into a horizontal and diagonal direction, and projecting a little beyond the rest of the coil terminates in a flat cap or nozzle, D^2 , (shown in detail in Fig. 7,) having a narrow horizontal slot, d^2 , extending quite across it and notching its sides to a slight depth. The object of 75 the upper horizontal turn, which has been described, is to brace the coil between the boiler and the wall.

The pipe of which the coil is composed should 80 be somewhat larger than that through which the steam enters it, in order to give room for the expansion of the steam. If the horizontal pipe c is half an inch in diameter, the pipe of the coil may advantageously be three-quarters 85 of an inch. Common single pipe may be used for the coil; but double pipe will be found preferable. The steam, passing from the dome through the pipe C into the coil within the fire-box, ascends and descends through the coil in 90 the direction shown by the arrows in Fig. 2, being all the time directly over the fire, and

in its passage becomes superheated. It then escapes through the slot d^2 and spreads in a sheet over the whole surface of the burning coals, mingling with the smoke and gases as they rise, and causing a perfect combustion of them before they can pass over the bridge.

Inasmuch as the discharging-pipe of the coil projects diagonally and but a short distance from the corner of the fire-box, it throws its sheet of steam over practically the whole surface of burning coals. Other arrangements and proportions of this pipe and of the rest of the coil would give an effect the same in kind but inferior in degree. I have shown those which I deem best; but it will be understood that I do not limit myself to them.

Instead of the coil which I have shown, an annular drum might be used with similar effect, and other modifications which do not affect the principle of the invention will readily suggest themselves.

The apparatus which I have described is extremely simple and cheap, and I have found on trial that it is perfectly efficacious. For all the intense heat to which it is subjected within the fire-box a coil made of double pipe will be found to do satisfactory service; and when one coil is burned out, or nearly so, it can be removed and replaced with very little trouble and in a very short time. The removal is thus easily accomplished, for the reason that the coil is not permanently attached to any portion of the structure, but rests loosely on the shoe D' , and is held in place at its upper end loosely between the boiler and side wall of the furnace. It is simply required, therefore, to disconnect the service-pipe, when the coil may be lifted from its place and taken out through the openings of the furnace.

I am aware that many devices have heretofore been devised for throwing jets of steam into the fire-box and upon the burning fuel; but in all cases, so far as I am aware, the steam has been sprayed in, and, to greater or less

extent, directed down upon the fuel. By my apparatus I avoid the direct impingement of the steam upon the fuel and the simple spraying, by both of which the steam is simply diffused among the products of combustion with little or no effect. By means of the horizontal slotted nozzle I direct an unbroken sheet of steam continuously and with force across the rising products of combustion, and thus effectually check them and cause them to be consumed, and in this unbroken horizontal sheet, in contradistinction from the old method of spraying, the main principle of my invention consists.

What I claim as my invention, and desire to secure by Letters Patent, is—

1. The steam-heater D , in combination with the shoe D' , attached to the grate-bars of the furnace, and the boiler A , between which and the furnace-wall the upper end of the heater is held, substantially as described.

2. An apparatus for consuming or preventing smoke, consisting of a single steam holder or receiver, D , arranged within the furnace and at one corner of the draft end thereof, and provided with a horizontal fan-jet nozzle, D^2 , extending diagonally from the receiver and arranged just above the bed of coals, whereby the steam is superheated and then delivered in an unbroken horizontal sheet just over the coal-bed, but not in contact therewith, substantially as and for the purpose set forth.

3. In combination with the fire-box of a furnace, a superheater, steam-pipes for supplying said superheater, a discharge-pipe attached to said superheater, having a horizontally-slotted nozzle arranged a little above the grate, and adapted to discharge an unbroken and a continuous sheet of steam horizontally over practically the whole fire, substantially as described.

CANUTE OLSON.
